UNITED STATES PATENT OFFICE.

ALBERT HOERMLE, OF CINCINNATI, OHIO, ASSIGNOR TO THE LEO CANDA MFG. CO., OF CINCINNATI, OHIO.

PICTURE-EXHIBITING DEVICE.

SPECIFICATION forming part of Letters Patent No. 718,763, dated January 20, 1903.

Application filed January 28, 1901. Serial No. 45,156. (No model.)

To all whom it may concern:

Be it known that I, ALBERT HOERMLE, a citizen of the United States, and a resident of Cincinnati, Hamilton county, State of Ohio, have 5 invented certain new and useful Improvements in Automatic Picture-Exhibiting Devices; and I do declare that the following is a clear, full, and exact description of the invention, such as will enable others skilled in the 10 art to which it appertains to make and use the same, attention being called to the accompanying drawings, with the reference-numerals marked thereon, which form also a part of this specification.

15 This invention relates to automatic picture-exhibiting devices which may be set in operation by payment of a certain coin deposited in a designated place, permitting a series of pictures to be viewed.

20 In my device the pictures are on a ribbon attached with its ends to two rollers placed parallel to each other, and upon one of which rollers the ribbon is normally wound. Mechanism which may be rendered operative by 25 the payment of a coin or otherwise causes the empty roller to rotate, whereby said ribbon is wound upon it, the pictures being viewed while passing through the space from one roller to the other. At the end of the operation 30 and when all pictures have been viewed the other or first roller is caused to rotate, whereby the ribbon is wound again upon such roller to be ready for the next succeeding exhibition.

35 In the following specification and particularly pointed out in the claims at the end thereof is found a full description of my invention, together with its operation, parts, and construction, which latter is also illustrated in the accompanying three sheets of drawings, in which—

Figure 1 is a side elevation of the device with the inclosing outer case in section. Fig. 2 is a similar view, the plane of view being taken 45 farther back to show parts partly obscured in the preceding view, for which purpose the frame of the apparatus is shown in section and parts nearest the observer in the preceding view are removed. Fig. 3 is a front view 50 of the device with the outer case in section. Fig. 4 is a top view, the case also in section

and the lens-holder and connected parts entirely removed. Fig. 5 is a vertical cross-section, and Fig. 6 is a top view of the coin-receiving hopper. Fig. 7 is a view similar to 55 Fig. 1, showing certain parts of the mechanism in intermediate position. Fig. 8 is a side elevation of the operating lever-handle and certain connected parts operating in conjunction therewith. Fig. 9 is a detail view showing end of one of the rollers with parts broken away, illustrating manner of attaching picture-ribbon. Figs. 10 and 11 show at reduced scale, respectively, a front and end elevation of the device complete. 65

The pictures, preferably stereoscopic views, are contained upon a ribbon 10, which is normally wound around a roller 11, to which also one of its ends is secured. This roller is mounted upon a shaft 12, supported in parts 70 of the general frame 13. The other end of the ribbon is attached to another roller 14, mounted upon a shaft 15, and also supported in parts of the general frame 13. For showing the pictures the ribbon is wound upon 75 the exhibiting-roller, being this roller 14, which winding is effected by rotating the same. The ribbon unwinding from roller 11 and while passing to the other roller permits the pictures to be seen through suitable view-glasses. The pictures may be illuminated by 80 any suitable artificial light. In this case they are rendered visible by having the ribbon of transparent material and a window 21, closed with ground glass, placed in the outer housing and behind the exposed part of the ribbon. The rotation of the exhibiting-roller is by a motor driven by a weight or spring and wound for every exhibition by means of a pivotally-supported lever-handle 22, accessible from the outside. By preference the 85 actuation of this handle is, however, operatively effective for winding the motor only in case the proper coin has been previously inserted through a slot 23 into the coin-chute 90 24, and is conveyed thereby to a certain position, in which it is capable of and does aid in transmitting operatively the actuation of the handle to the motor. For such purpose the coin is arrested during its descent through 95 the coin-chute by a stop projecting thereinto and beyond which the coin cannot drop. At 100

and above this stop part of one of the flat sides of the coin-chute the rear side in this case is removed, rendering the coin-chute open thereat to an extent permitting exit of a coin flatwise. Normally, however, this open part of the coin-chute is held closed by the perforated or forked end of an angle-lever 25, pivotally supported on a pin 26 and carrying at its other end a segmental rack 27.

10 Integrally or otherwise rigidly connected to lever-handle 22 or to a rock-shaft formed in this case by the pivot-pin 26, and so as to move with the lever-handle, is a lever 28, forming at one of its ends a finger 29, so located and curved as to be adapted to pass through an opening in one of the flat sides, the one in front of the coin-chute, which opening is opposite and in line with the opening or space in the end of forked lever 25, lying against the open rear side of the coin-chute. The area of these openings and the end of finger 29 are considerably smaller than the area of the smallest coin to be used, so that when the progress of this latter through 15 the coin-chute is arrested by the stop therein the coin will rest between these openings and in a position which closes passage therethrough. In this position the coin is also between the open end of lever 25 and the end 20 of finger 29, as shown in Fig. 1, so that when this finger in consequence of a handle operation moves against the coin this latter will be pushed rearwardly and out of the coin-chute, moving against and displacing at the same 25 time the forked lever 25, as shown in Fig. 2. This raises the segmental rack 27, and being connected by means of a connecting-rod 31 to a spring 32 this latter and the parts connected thereto are at once put under tension. This constitutes the winding of the 30 spring-motor, and, as will be seen, it is made in this case dependent on the insertion of a coin, which must also be of the proper size corresponding to the denomination intended, 35 so as to be held in and occupy the necessary position, which is between the open end of lever 25 and the end of finger 29. Upon release of the lever-handle, this latter together with finger 29 are quickly returned to their 40 original positions by a spring 33. Lever 25 cannot immediately follow in this return movement by reason of the engagement of its rack 27 with a pinion 34, which has meanwhile taken place and which engagement 45 causes a separation between said lever and finger 29, whereby the coin is liberated. (See Fig. 7.) The aforementioned stop holding the coin in the coin-chute may be simply a closure of this latter; but when either one 50 of a larger or smaller coin—for instance, a nickel or a cent—are to be used, the coin-chute is merely sufficiently contracted. This contraction is edgewise and sufficient only to stop a nickel, but permitting a cent to freely 55 pass through. In order to stop a cent, I provide a spring-wire 35, connected with its upper end to the coin-chute and its lower end

bent and adapted to project through an opening into the coin-chute. When not needed, the end of this wire is simply lifted out of this opening and moved laterally, so as to rest against the coin-chute. (See Fig. 3.) Pinion 34 is loosely mounted upon a stud-shaft 36, and beside it, loosely mounted, there is a cog-wheel 37, engaging a pinion 38 on shaft 15, 70 upon which the exhibiting-roller 14 is mounted. By means of a customary pawl 39 on wheel 37 and ratchet-wheel 41 on pinion 34 the action of the spring-motor is now transmitted from pinion 34 to cog-wheel 37 and 80 from there reaches finally the exhibition-roller, which now starts to rotate, taking on the ribbon which unwinds from the other roller. The pictures while passing through the space from one roller to the other move 85 through the field of vision and become observable behind the view-glasses. The rotation in reverse direction of pinion 34, which takes place when segmental rack 27 is raised during the winding of the spring-motor, is 90 not transmitted to cog-wheel 37 by reason of the described pawl-and-ratchet connection between the two, which is not operative at that time. This unwinding of the ribbon from roller 11 causes, of course, this latter to 95 rotate, which rotation I utilize to also rotate a sheave 42, mounted upon shaft 12, which rotation causes a cord 43 to wind upon said sheave. This cord passes over a guide-pulley 44 and carries a weight 45 on its other 100 end, which weight is thus raised. The exhibiting-roller continues to rotate until segmental rack 27 has resumed its normal position against a stop 46 when it is out of gear with pinion 34. At that time roller 14 also 105 ceases to rotate and the pictures have all passed. The resistance of the spring not being present any more, weight 45 is free to drop, which it does at once, thereby unwinding the cord from sheave 42. This causes rotation of roller 11, whereby the ribbon is 110 quickly wound back again upon it, so as to be ready for the next exhibition. Roller 14 is free to follow this rotation, since cog-wheel 37 is only loosely mounted and not otherwise 115 operatively connected.

In order to have all operations exactly of the same duration, so that the ribbon always comes back to the same starting-point, it is necessary that the extent of motion or number of revolutions while winding upon one roller is equal to the extent of motion while winding again upon the other roller. To obtain this, I arrange that cog-wheel 37 makes each time a full revolution, rotating first in 120 one direction and then in the other, coming each time to a dead stop by having a pin 47 on it engaging a stop 48. Since the presence of this pin would prevent cog-wheel 37 from going through a full revolution each 125 time, I provide a pivotal connection for stop 48, allowing it to yield to an extent which equals the thickness of pin 47, to which extent each revolution would otherwise be

short. This yield is limited to the proper distance by limiting the swing of stop 48 between pins 49. (See dotted lines in Fig. 2.)

In order to have the rotation of the exhibition-roller of a speed sufficiently slow for convenient observation of the pictures, I retard the same by means of an interposed gear-train contained in a movement-frame 51, taking its initial start of motion from any of the rotary parts described, preferably from shaft 15, and ending in a fan 52 on shaft 53. Between these two limits there is a number of sets of engaging cog-wheels and pinions transmitting the motion from shaft 15 to shaft 53. The connection of this gear-train to shaft 15 is by means of a ratchet-wheel 54 engaging a pawl 55 on the first cog-wheel of the gear-train, and which connection is so arranged that the rotation of shaft 15 is transmitted to said gear-train only at the time when the former is positively rotated by the spring-motor during the exhibition of the pictures; otherwise—that is, at the time when roller 14 is rotated by the ribbon while unwinding from it—this rotation is not transmitted to the gear-train.

It is necessary that all manipulations connected with the winding of the motor and the insertion of the coin, when such is used, are properly performed to insure a complete winding of the spring and to prevent in the latter case the premature release of the coin where its presence and coaction is made necessary for the winding. Therefore it is arranged that the handle after once started cannot be returned from any intermediate position which otherwise would release the coin until it has been fully moved through the intended range of its movement and as required to completely wind or set under tension the spring of the motor. This is accomplished by a pawl-and-ratchet device, the latter in shape of a toothed segment 56, being simply a rearward extension of lever 28, both being supported and rigidly connected to pivot-pin 26, which forms a rock-shaft and to which lever-handle 22 is also rigidly connected, so that all move together. The complementary pawl, numbered 57, is normally held in engagement with this segmental ratchet and remains so until the lever-handle has been moved through its full stroke, holding it meanwhile against reverse rotation at every intermediate point to which it has been advanced. At the end of this movement a projection 58 on it strikes the point of said pawl and throws it out of engagement, by which time segmental rack 27 has been fully raised to the intended extent and main spring 32 is set under tension. The handle may now be released, when spring 33 carries it and the other parts connected therewith quickly to their respective normal positions, separating also the end of finger 29 from the forked end of angle-lever 25 and liberating the coin. When so returning to normal positions, a hook-shaped projection 59 at the other upper end of seg-

mental ratchet 56 engages and strikes pawl 57 back of its point, thereby throwing it again in position for ready engagement with the ratchet during the next operation of the parts. To hold pawl 57 in either one of these positions and to prevent it from being thrown out too far and beyond reach of projection 59, there is a locking-pawl 61, having two notches 62, either one of which is occupied by the heel of pawl 57 and whereby this latter is held in either one of its two positions, as shown in Figs. 1 and 2. This locking-pawl is pivotally supported and held by means of a spring 63 against the heel of pawl 57, thus being capable of yielding to the motion of the former when its heel slides from one of the notches 62 into the other one, and at the same time it also holds pawl 57 yieldingly in either one of its positions. It is desirable that all these manipulations as connected with the winding and setting of the spring be complete before the ribbon, with the pictures, starts to move. To obtain this, the start of operation is made dependent on the return of the handle to its original position, and the means for such purpose consist, substantially, of a stop forming an obstruction to the movement of the mechanism and which stop is moved into operative position during the first part of the winding manipulation and remains so until moved out of the way in consequence of the handle arriving in its original position. This feature of the device consists of a stop 64, being a projection extending from one of the rotating parts, preferably shaft 53, and operating in conjunction with a pivotally-supported trigger 65, which is normally held out of reach of this stop by a spring 66. By means of one of the parts which moves during the winding operation—as, for instance, by means of one end of segmental rack 27, pushing against a pin 67 on this trigger, as shown in Fig. 2—one end of this latter is raised and swung into engagement with a trip-lever 68, a notch in which catches a lateral projection on said trigger, which projection may be the other end of pin 67. This movement of the trigger causes its upper end to swing toward shaft 53, so as to come within the rotary path of stop 64 thereon, thus preventing rotation of said shaft. Since this shaft forms part of the gear-train constituting the speed-regulating device, it is clear that this latter becomes effectually locked, and by reason of its pawl-and-ratchet connection 54 and 55 to shaft 15, which connection is now operative, rotation of the exhibition-roller is also prevented; but for this locking of the movement the parts would start to operate at once as soon as segmental rack 27 has reached its highest point and before the lever-handle has been returned to its normal position. Such immediate start is, however, prevented by trip-lever 68, which still holds trigger 65 into the path of stop 64 and continues to do so until acted upon in a manner to release the trigger. This release is timed to occur at the moment

when the lever-handle is arriving in its normal position and is effected by it or by parts moving with it at the time. For such purpose I use the end of lever 28 at a point where it connects to finger 29 and which end at the last moment and when arriving in its normal position strikes against the downwardly-turned end of the trip-lever and lifts the same off of pin 67 of trigger 65. Spring 66 pulls now this latter 15 immediately out of the path of stop 64, thus relieving the gear-train and permitting the device to operate. Rack 27 is pulled down by the main spring and roller 14 is positively rotated, taking on the pictures which it 20 unwinds from roller 11. This latter while so rotating winds cord 43 upon sheave 42 on its shaft, thereby raising weight 45. When rack 27 has passed out of gear with pinion 34, then said weight drops at once, positively rotating 25 roller 11, which takes the pictures back from roller 14, both rollers now rotating in directions opposite to their previous rotation.

It is preferable to provide for possibility of removal of the upper roller, for which purpose I have shaft 15 in two sections, held together by any suitable coupling 83.

The connection of the ends of ribbon 10 to the rollers is such as to permit detachment for interchange and renewal of pictures. 30 For such purpose there are bars 84, one at each end of the ribbon and each provided with buttons 85 at their ends adapted to pass into openings of spring-catches 86, which openings communicate with slots to be occupied by the shanks of said buttons.

The whole apparatus is inclosed within an outer casing, access to which is had by means of a door 87, which is simply one of the sides or ends of this casing and is not hinged or 40 otherwise permanently connected to this latter, except at such times when temporarily held thereto by a lock. The mechanism by such parts of its frame next adjacent to this door is permanently connected thereto and 45 access is therefore by simply unlocking this door, moving it away from the casing, the mechanism connected thereto following. This involves a sliding movement of the mechanism within the casing, and since such requires a close fit of the parts I make the base 50 of frame 13 adjustable to the clear inside width of the casing, which is done by having a special frame-section 88 for such purpose which is adjustably connected to the other frame.

Having described my invention, I claim as new—

1. A picture-exhibiting device, consisting of an outer case, a ribbon which carries the 60 pictures, bars at each end of this ribbon, buttons at the ends of these bars, two rollers supported with a space between them, each having a spring-catch attached near each of its ends, an opening in the free end of each of 65 these catches adapted to receive the buttons mentioned and whereby the picture-ribbon is detachably secured to the rollers, the length

of this ribbon being largely in excess of the space between the rollers, which excess is normally wound upon one of these latter and 70 mechanism to wind this ribbon from one roller onto the other and back again.

2. In a coin-controlled picture-exhibiting device, the combination of a ribbon carrying pictures, rollers spaced apart to which the 75 ends of this ribbon are secured, mechanism whereby this ribbon is wound from one roller onto the other, and means whereby it is normally returned upon the first roller, a frame to which all these parts are secured and 80 whereby they are supported, an outer case which receives this frame, which latter is attached to one of the sides or ends thereof, such end having no permanent connection with the case, so that the same with the frame 85 attached may be removed as a whole by being slid endwise out of the case, a lock whereby this removable end may be temporarily held to the case, an opening in this latter provided with view-glasses through which the pictures 90 may be seen, and an adjustable frame-section 88 to adjust the width of the frame to the inside of the case.

3. A picture-exhibiting device, consisting of an outer case, two rollers supported with- 95 in, with a space between them, a ribbon which carries the pictures secured with its ends to each one of these rollers, the length of said ribbon being largely in excess of the space between the rollers, which surplus is normally carried upon one of these latter, an opening in the outer case opposite the space between the two rollers and provided with view-glasses, a spring-motor for rotating the empty roller to wind upon it the ribbon from 105 the other roller, such rotation being at slow speed, so that the pictures become visible while passing behind the view-glasses and means operating automatically and at increased speed for winding the ribbon back 110 again upon the first roller.

4. A picture-exhibiting device, consisting of an outer case, two rollers supported with- 115 in, with a space between them, a ribbon which carries the pictures secured with its ends to each one of these rollers, the length of said ribbon being largely in excess of the space between the rollers, which surplus is normally carried upon one of these latter, an opening in the outer case opposite the space between the 120 two rollers and provided with view-glasses, a spring-motor for rotating the empty roller to wind upon it the ribbon from the other roller, a lever-handle whereby the same may be wound, a drive-shaft adapted to be rotated by 125 said spring-motor, an operatively-connected gear-train to control the speed of rotation of said drive-shaft and a stop adapted to lock said gear-train against rotation and hold it so until released by the lever-handle when this 130 latter is returned to its normal position.

5. A picture-exhibiting device, consisting of an outer case, two rollers supported with- 135 in, with a space between them, a ribbon which

carries the pictures secured with its ends to each one of these rollers, the length of said ribbon being largely in excess of the space between the rollers, which surplus is normally carried upon one of these latter, an opening in the outer case opposite the space between the two rollers and provided with view-glasses, a spring-motor for rotating the empty roller to wind upon it the ribbon from the other roller, a lever - handle whereby the same may be wound, a segmental ratchet on this latter, a pawl remaining in engagement therewith during the operative manipulation of the lever-handle and preventing return of the same from any intermediate position and means disengaging said pawl after that manipulation to permit return of the lever-handle to its normal position.

6. A picture-exhibiting device, consisting of an outer case, two rollers supported within, with a space between them, a ribbon which carries the pictures secured with its ends to each one of these rollers, the length of said

ribbon being largely in excess of the space between the rollers, which surplus is normally carried upon one of these latter, an opening in the outer case opposite the space between the two rollers and provided with view-glasses, a spring-motor for rotating the empty roller to wind upon it the ribbon from the other roller, a lever - handle whereby the same may be wound, a drive-shaft 15, a pinion 38 and cog-wheel 37 for transmitting the action of the spring-motor to the drive-shaft, said cog-wheel loosely mounted, so as to transmit such action only in one direction, means whereby said cog-wheel is returned to its starting-point and a pin 47 and a yielding stop 48 for defining such position.

In testimony whereof I hereunto set my hand in the presence of two witnesses.

ALBERT HOERMLE.
